UNITED STATES PATENT OFFICE.

RALPH W. EMERSON, OF ROCKFORD, ILLINOIS.

DESIGN FOR A TABLE-WASHSTAND.

SPECIFICATION forming part of Design No. 23,222, dated April 24, 1894.

Application filed March 12, 1894. Serial No. 503,364. Term of patent 7 years.

To all whom it may concern:

Be it known that I, RALPH W. EMERSON, a citizen of the United States, residing at Rockford, in the county of Winnebago and State of Illinois, have invented and produced a new and original Design for Table-Washstands, of which the following is a specification, reference being had to the accompanying drawing, showing a part thereof.

10 The figure represented in the drawing shows the wash stand in its open position.

The features of my design consist in the outer contour of the stand, which consists of sides 1, and ends 2, forming a receptacle.

15 The lower edges of the sides and ends are of irregular shape and on their faces are located scroll work which conform to the lower edges. To each corner of the receptacle is secured a

leg 3 their upper portions bowing outward, and to their lower portions is secured a shelf 4, 20 having its edges concave and formed with a bead molding 5. The upper portion of the receptacle has an edge 6, of irregular shape its corners being rounded. Over this receptacle is placed a top 7, having its edges conforming to the formation of the upper edge of the receptacle and upon its under face is secured a panel 8, of molding.

I claim as my invention—

The design for a table wash-stand herein 30 shown and described.

RALPH W. EMERSON.
